UNITED STATES PATENT OFFICE.

ARTHUR BARTELS, OF WESTGATE, IOWA.

WAGON-STANCHION.

1,251,463.

Specification of Letters Patent.

Patented Jan. 1, 1918.

Application filed April 20, 1917. Serial No. 163,521.

To all whom it may concern.

Be it known that I, ARTHUR BARTELS, a citizen of the United States, residing at Westgate, in the county of Fayette and State 5 of Iowa, have invented a new and useful Wagon-Stanchion, of which the following is a specification.

The subject of this invention is a wagon 10 stanchion in which a supporting frame operates with a stanchion, and the objects of the invention are, first, to provide a stanchion supporting frame which may be readily placed in a wagon and removed therefrom, second, to provide a stanchion 15 supporting frame which may be quickly folded up when not in use, third, to provide a stanchion supporting frame which may be quickly assembled and disassembled, and fourth, to provide a simple and efficient 20 stanchion frame.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, with 30 out departing from the spirit of the invention.

One practical embodiment of my invention is shown in the accompanying drawings, wherein:—

35 Figure 1 is a view in elevation of the device, a slight portion broken away to show the attaching means.

Fig. 2 is a plan view of the device showing the same folded.

40 Referring to the drawings by numerals:—

A base or flooring 1 is provided, which is formed of planks tied together at one end by a cross piece 2, to which the planks are bolted or otherwise secured. At the other 45 end an angle iron 3 is secured transversely of the flooring 1. A rod 4 is secured, near each end of the angle iron 3, to the up-standing web, and each rod is formed with an angled end in which an aperture is provided for the reception of a key 5.

The frame consists of side uprights 6, connected at their upper ends by a cross piece 7, and braced by the inclined pieces 8 which extend between each side piece and 55 the cross piece, as shown. The various parts of this frame are preferably made of angle

iron. In one web of each side piece 6, and near the bottom end, is provided an aperture for the reception of the angled end of rod 4. This connection pivots the frame to the 60 floor or base 1.

Secured at each side of the floor or base, toward the end opposite that at which the frame is pivoted, are rods 9—9, each of which is provided with an angled end, apertured to receive a key 10. The angled end of each rod 9 projects through an aperture formed in one end of an inclined brace or strut 11—11, to the other end of each of which is secured an angled attaching lug 12 apertured to receive a key 13. Each lug 12 projects through an opening formed at a medial point of each upright 6, and is detachably held in place by a key 13.

A stanchion, indicated generally at 16, is 75 secured within the frame, preferably through chains 15 and 16. The chain 15 has its end link secured to the cross bar 7 by means of a bolt 17, or otherwise, while the chain 16 is detachably secured to the bar 80 3 by means of a lug 18 which passes through its end link and which is formed to receive a key 19, by which the link is retained in place.

In practice the device is used as follows:— 85 The frame is mounted in place by passing the ends of angle rods 4 through the apertures formed in the lower ends of the uprights 6, and keys 5 are inserted to secure the frame in place. The lower end of the 90 stanchion is then secured by placing the end link of chain 16 over the lug 18 and securing the same in place by the key 19. The struts 11 are positioned with their lower ends engaged by the rods 9, to which they 95 are keyed by the keys 10, and the lugs 12, at their upper ends, are inserted in the apertures formed in the uprights 6 for their reception. The keys 13 are then inserted. The neck of an animal may then be secured 100 within the stanchion in the usual manner. When not in use, the keys 13 may be withdrawn and the device folded, as seen most clearly in Fig. 2. By also withdrawing the keys 5, 10 and 19 the device may be completely taken apart.

Having described my invention, what I claim as new and desire to secure by Letter Patent, is:—

1. A wagon stanchion, comprising a base, 110 a frame pivoted to the base, and means for securing a stanchion within the frame.

2. A wagon stanchion, comprising a base, a frame pivoted to the base, struts pivoted to the base and detachably secured to the frame, and means for securing a stanchion within the frame.
3. A wagon stanchion, comprising a base, a frame detachably secured to the base, struts detachably secured to the base and frame, and means for securing a stanchion within the frame.
4. A wagon stanchion, comprising a base,

a frame pivotally secured to the base, detachable means for securing the frame in an upright position, and means for securing a stanchion within the frame. 15

In testimony that I claim the foregoing as my own, I have hereto affixed my signature in the presence of two witnesses.

ARTHUR BARTELS.
